JOSEPH P. BRADEN, OF ST. PAUL, AND WILLIAM D. PALMER, OF MINNEAPOLIS,
MINNESOTA.

RAIL-CLAMP.

1,074,407.

Specification of Letters Patent. Patented Sept. 30, 1913.

Application filed June 17, 1913. Serial No. 774,212.

To all whom it may concern:

Be it known that we, JOSEPH P. BRADEN and WILLIAM D. PALMER, citizens of the United States, and residents, respectively, of 5 St. Paul, in the county of Ramsey and State of Minnesota, and Minneapolis, in the county of Hennepin and State of Minnesota, have invented a new and Improved Rail-Clamp, of which the following is a full, clear, and 10 exact description.

This invention relates to rail clamps adapted for use in connection with steam shovels and similar machinery for maintaining the same immovable on the track.

15 The invention has for its general object to improve and simplify the construction of devices of this character so as to be comparatively inexpensive to manufacture, of durable and substantial design and capable 20 of being readily attached to or detached from the rail.

Another object of the invention is the provision of a clamping device of the double jaw type having novel means for holding the 25 jaws closed on a rail and additional means for wedging the jaw elements on the rail.

With these objects in view, and others as will appear as the description proceeds, the 30 invention comprises various novel features of construction and arrangement of parts which will be more fully described herein-after and set forth with particularity in the claims appended hereto.

In the accompanying drawings, which 35 illustrate one embodiment of the invention, and wherein similar reference characters are employed to designate corresponding parts throughout the several views, Figure 1 is a side view of the rail clamp shown applied 40 to a rail; Fig. 2 is a front view of the device; Figs. 3 and 4 are vertical sections on the lines 3-3 and 4-4 of Fig. 2; and Fig. 5 is a top plan view of the device.

Referring to the drawing, A and B designate 45 jaw members of the clamp, one member having at its upper portion a hinge eye or knuckle 1 and the other hinge eyes or knuckles 2, which are spaced apart to receive between them the knuckle 1, and passing 50 through the knuckles, which have pintle openings 3, is a pintle in the form of a bolt 4, whereby the two jaw members are hingedly connected together. Each jaw member has an inverted U-shaped handle 5 formed 55 integrally or otherwise connected with its

jaw member, and these handles or grips are so related that they can be gripped by the hands to force the rail-engaging extremities or jaws 6 apart. The inner or opposed faces of the jaws 6 have recesses 7 to conform to 60 the head of an ordinary T-rail 8.

The jaw elements A and B are locked closed by a pair of parallel locking devices or bolts 9 which are journaled in openings 10 in the jaw element B, there being on one 65 end of each rotary locking member 9 a laterally-extending lug or head 11 which is movable through a slot 12 in the jaw element A. This slot is elongated vertically and the heads 18 of the locking bolts can 70 pass into and out of the slots when such heads are also disposed vertically. When the jaws are in closed position, as shown in Fig. 1, the heads 11 of the bolts are turned 45° more or less so as to throw the heads 11 75 out of alignment with the slots 12 and into engagement with the outer face of the jaw A, whereby the jaws are held together. On the ends of the locking members or bolts 9 opposite from the heads or lugs 11 are 80 crank arms 13 which are united by a link 14 to maintain parallelism between the lugs 11 of the bolts, and also to enable the bolts to be moved simultaneously to or from locking position. One of the crank arms is extended 85 into a handle 15, whereby the bolts can be conveniently manipulated. On the jaw element B are provided stops 16 and 17 between which the handle-carrying crank 14 is movable, whereby the lugs limit the locking and unlocking movement of the bolts. 90

The jaw elements A and B are provided with alining openings 18 at their jaw portions, which openings intersect the recesses 7, and slidably in these openings 18 is a 95 wedge 19 that is permanently maintained on the jaws by a transverse pin 20 in the smaller end of the wedge, and by means of the larger end of the wedge, which larger end is of such dimensions that it cannot 100 pass through the openings 18, and the pin 20 being longer than the width of the wedge so as to form lugs which engage the jaw element A and prevent the wedge from becoming detached. After the jaw elements are 105 clamped to a rail the wedge 19 is driven in a direction to wedge the same between the tread surface of the rail 8 and the upper surface or wall of the recess or recesses 18 in the body of the clamp. In this man- 110

ner the clamp is firmly held against longitudinal movement on the rail, and consequently the steam shovel or other machinery with which the clamp is used is firmly held 5 in place. In opening the clamp the wedge is first driven out by striking the thin end thereof and the projections formed by the ends of the pin 20 engage under inclined surfaces or abutments 21 on the jaw element A, 10 and in this manner the wedge is held in such a position that it does not interfere with the free opening of the jaws, for without the abutments or lugs 21 the wedge assumes a centered position, which renders the opening 15 of the jaw elements difficult.

From the foregoing description taken in connection with the accompanying drawings, the advantages of the construction and method of operation and of the device shown 20 will be readily understood by those skilled in the art to which the invention appertains, and while we have described the principle of operation, together with the device which we now consider to be the best embodiment 25 thereof, we desire to have it understood that the device shown is merely illustrative, and that such changes may be made when desired as are within the scope of the appended claims.

30 Having thus described our invention, we claim as new and desire to secure by Letters Patent:

1. A rail clamp comprising hingedly connected jaw members, locking bolts rotatably 35 mounted on one member, the other member having slots to receive the bolts, and the bolts having lugs movable into and out of the slots and engageable with the outer surface of the slotted member, and means for 40 operating the bolts simultaneously.

2. A rail clamp comprising hingedly con-

nected jaw members, locking bolts rotatably mounted on one member, the other member having slots to receive the bolts, and the bolts having lugs movable into and out of 45 the slots and engageable with the outer surface of the slotted member, crank arms on the bolts, and a connection between the arms for moving the bolts simultaneously.

3. A rail clamp of the class described comprising movably connected jaw members, means for locking the members in closed position, said members having registering openings in their jaw portions, a rail-engaging wedge mounted in the said openings, 55 means on the smaller end of the wedge for preventing detachment of the latter from the jaw members, and the larger end of the wedge being of greater dimensions than the said opening to prevent the wedge from 60 passing therethrough, and inclined abutments on one of the jaw members for engagement with the said means on the wedge when the latter is in fully released position, whereby the jaw members can be opened 65 without the wedge interfering.

4. A rail clamp comprising hingedly connected jaw members, a plurality of locking means carried by one member and engageable with the other member, and connecting 70 means between the locking means for causing simultaneous movement thereof to or from locking position.

In testimony whereof we have signed our names to this specification in the presence of 75 two subscribing witnesses.

JOSEPH P. BRADEN.
WILLIAM D. PALMER.
